CLAIM

The ornamental design for a credit card with case, as shown and described.

DESCRIPTION

FIG. 1 is a top view of the credit card and case of the present invention with the card in the fully closed position within the case;

FIG. 2 is an upper side view of the card and case of FIG. 1; FIG. 3 is a lower side view of the card and case of FIG. 1; FIG. 4 is a top view of the card and case of FIG. 1 with the card in the partially open position;

FIG. 5 is a top view of the card and case of FIG. 1 with the card in the fully open position;

FIG. 6 is a top view of the card and case of FIG. 1 with the card removed from the case in an exploded condition;

FIG. 7 is a bottom view of the card and case of FIG. 1 with the card in the fully open position;

FIG. 8 is a bottom view of the card and case of FIG. 1 with the card in the fully closed position; and,

FIG. 9 is a perspective bottom view of the card and case of FIG. 1, showing the location of a key ring.

The broken lines showing environment in the drawings are for illustrative purposes only and form no part of the claimed design.
